DISPENSING CONTAINER FOR CLEANSING POWDER OR THE LIKE

Victor Koenigsberg, Franklin Square, N.Y., assignor to Colgate-Palmolive Company, New York, N.Y., a corporation of Delaware

Filed Jan. 22, 1962, Ser. No. 68,415

Term of patent 14 years

(Cl. D58—17)

Fig. 1

Fig. 3

FIG. 1 is a top plan view of the dispensing container for cleansing powder or the like embodying my new design;

FIG. 2 is a front elevation thereof; and

FIG. 3 is a central vertical cross-section thereof.

I claim:

The ornamental design for a dispensing container for cleansing powder or the like, as shown and described.
